CLAIM

The ornamental design for a UV panel light, as shown and described.

DESCRIPTION

FIG. 1 is a front elevational view of a first embodiment of a UV panel light, showing our design;
 FIG. 2 is a rear elevational view thereof;
 FIG. 3 is a right side elevational view thereof;
 FIG. 4 is a left side elevational view thereof;
 FIG. 5 is a bottom plan view thereof;
 FIG. 6 is a top plan view thereof;
 FIG. 7 is a bottom-front-right perspective view thereof; and,
 FIG. 8 is a rear-top perspective view thereof.
 The broken lines throughout the figures show portions of the UV panel light that form no part of the claimed design.

1 Claim, 6 Drawing Sheets
